UNITED STATES PATENT OFFICE.

HYMAN I. RAPPAPORT, OF BROOKLYN, NEW YORK, ASSIGNOR OF NINETY PER CENT
TO JENNIE ROSENTHAL, OF BROOKLYN, NEW YORK.

BLINDSTITCHING MACHINE.

Application filed April 28, 1923. Serial No. 635,268.

To all whom it may concern:

Be it known that I, HYMAN I. RAPPAPORT, a citizen of the United States, and resident of the borough of Brooklyn, city of New York, in the county of Kings and State of New York, have invented certain new and useful Improvements in a Blindstitching Machine, of which the following is a specification.

10 This invention relates to a blind stitching machine. Its organization is characterized by means to vary the stroke of the feed of the material operated upon. It is further characterized by spring actuated work supported plates that can slide in vertical planes and simultaneously swing in said planes. The invention contains an oscillating ridge forming head with teeth which pushes forwardly the material operated 20 upon.

The object of the invention is the production of a blind stitching machine, in which the length of the stitches can be varied, by a simple adjustment to vary the lengths of the 25 strokes of the feed dog of the machine.

Fig. 1 represents a side elevation of an exemplification of the blind stitching machine with a section as on the line 1—1 of Fig. 9 and a pair of elements omitted; Fig. 30 2 shows same details with a section as on the line 2—2 of Fig. 9; Fig. 3 is a top plan view of Fig. 2; Fig. 4 indicates a front elevation of the machine with a section as on the line 4—4 of Fig. 9; Fig. 5 indicates a front elevation of a detail; Fig. 6 is a top plan view of Fig. 5; Fig. 7 shows a front elevation of a detail; Fig. 8 represents a top plan view of Fig. 7, Fig. 9 shows a top plan view of the machine and Fig. 10 represents an enlarged section on the line 10—10 of Fig. 1.

The main frame of the machine comprises the front member 20 and the rear member 21 connected by the base plate 25 having the projecting lugs 26 and the central opening 27.

45 A body portion 28 of the main frame joins with the rear member 21. Journal lugs 29 and 30 are formed with the front member 20 and journal bearings 31 and 32 are formed with the rear member. A front journal bearing 33 with the projecting lug 34 and the rear journal bearing 35 are formed with the body portion 28. A journal lug 36 extends up from the journal bearing 35 and supports a thread tensioning de-

vice 37. A thread guide 38 extends from the bearing 33 and a thread guide 39 extends from the lug 36.

A main driving shaft 40 is journaled in the bearings 31 and 32 and has fastened thereto the usual driving pulley 41 and balance wheel 42.

An adjustable table 45 has formed therewith the journal bearings 46 and 47 at one end, and the cavity 48 at the other end. A shaft 49 is fastened in the lugs 29 and 30, 65 has hinged thereon the bearings 46 and 47 of the table 45. A hook bolt 50 is indicated with the hook 51 at one end and the threaded portion 52 at the other end. The bolt 50 at one end extends through the front member 70 20 of the main frame. A helical spring 58 encircles the shaft 49 and one end 59 thereof bears up against the table 45 and its other end 60 is engaged by the hook 51. A nut 61 is provided in the usual way for the portion 52 of the bolt 50 and the hook 51 engages the end 60 of the spring 58. An arm 62 extends from the table 45. An adjusting screw 63 is in threaded engagement with an opening in the front member 20 of the main 75 frame and one end thereof bears against the arm 62. By means of the spring 58, the bolt 50 and the screw 63 the table is maintained in requisite tension and position. A lug 64 extends from the lower face of the 80 table 45 and has extending therefrom the operating chain 65.

A supporting bracket is indicated in its entirety by the letter A and comprises the rear vertical wall 66, the vertical wall 67, 90 the upper shelves 68 and the lower shelves 70. The rear vertical wall 66 has its upper end fastened to the table 45 in the cavity 48. A journal bracket 72 extends from the table 45. A shaft 75 having the crank arm 76 95 with the crank pin 77 has its ends supported in bearings in the bracket 72 and the wall 67 of the bracket A.

An oscillating ridge forming head 82 is pivoted to the wall 67 of the bracket A, by 100 means of the screw pivot 83. The head 82 has formed therewith the projecting arcuate ridge 84 having the teeth 85 and the bifurcated leg 86 with the guide opening 87. The pin 77 of the crank arm 76 engages the guide 105 opening 87.

When the shaft 75 oscillates as will be explained, the crank pin 77 causes the ridge

forming head 82 to oscillate, to form ridges in the material operated upon as will be explained.

An eccentric 90 is fastened to the shaft 40.

5 A bracket 91 is fastened to the frame of the machine at the inner face of the journal bearing 32 and has formed at its upper end the lug 92.

10 A bifurcated lever having the members 94 and 95 is hinged to the lug 92 by means of the screw pivot 96. An adjusting arm 97 with the arcuate guide opening 98 extends from the member 94. A crank arm 100 is fastened to the shaft 75. A link 101 has one 15 end pivoted to the crank arm 100 by means of the screw pivot 102 and its other end is pivoted to arm 95 by means of the screw pivot 103. When the shaft 40 turns the eccentric 90, the lever with the members 94 and 20 95 oscillates on the pivot 96, causing the link 101 to receive a horizontal reciprocating movement resulting in the oscillations of the shaft 75.

25 A lever with the upper arm 108 and the lower arm 109 having the round nose 110 is pivoted to the body portion 28 of the frame of the machine by means of the screw pivot 111. A link 114 is indicated with the heads 115 and 116 and the latter is pinned to the 30 arm 108, by means of the screw pivot 117. The head 115 supports the pin designated in its entirety by the letter B, and comprises the hollow cylindrical portion 118 from which extends the cylindrical portion 119 35 with the flat side faces 120. The said portions have the interior thread 121. A screw 122 with the head 123 and flange collar 124 engages the thread 121. The head 115 of the link 114 engages the cylindrical portion 118 40 of the pin B and the portion 119 of said pin is located in the arcuate guide opening 98 of the arm 97. The said flattened side faces 120 bear against the adjacent sides of the arcuate guide opening 98. A spacer 125 45 bears between the guide 98 and the flange 124. By means of the screw 122, the pin B can be clamped to the adjusting arm 97 in different positions.

50 A feed dog 126 is indicated with the usual serrated lower face 127 and extends from an arm 128 formed with the flange 129. An arm is designated in its entirety by the letter C and comprises the body portion 130 which has formed therein the elongated 55 guide openings 131 and 132. The upper and lower walls of the latter opening are made arcuate to allow for the swinging of the arm C as will be explained. One end of the arm C has formed therewith the extended portion 60 133 at right angles to the body portion 130 and which has formed therewith the flange 134. The flange 134 has fastened thereto the flange 129 of the feed dog 126. An elongated 65 guide opening 135 is formed at one end of the said body portion 130, and an indent 136

is formed in said body portion above the guide opening 135. The arm C is slidably and hingedly connected to the body portion 28 of the frame of the machine by means of the screw pivot 138, which extends through 70 the guide opening 131 thereof. The nose 110 of the arm 109 engages the indent 136 of the arm C. A pin 139 extends from the body portion 28 and engages the guide opening 135. 75

An arm is indicated in its entirety by the letter D and has formed therewith an opening 142 and the bifurcated end with the members 143. A roller 145 is journaled to the arm D. The arm D bears against the arm C and is pivoted on the screw pivot 138 which extends through its opening 142. The roller 145 engages the guide opening 132 of the arm C and the members 143 of the bifurcated end of the arm D engage 80 the eccentric 90. When the shaft 40 rotates the said eccentric 90 causes the arm D to swing on the pin 138 in a vertical plane, by means of which the feed dog 126 is lightly 85 raised and lowered simultaneously with the oscillations of the shaft 75. 90

The arm having the members 94 and 95 oscillates simultaneously with the movements of the arms D and C and consequently the feed dog 126 moves forwardly in an upper 95 plane, then lowers and moves backwardly, after which it rises to the upper plane.

The lengths of the reciprocations of the feed dog 126 can be varied by clamping the pin B in different positions in the arcuate 100 guide opening 98 of the adjusting arm 97. The longest stroke of the feed dog is obtained when said pin B is located at the upper end of the opening 98. A pair of spring 105 actuated supporting plungers are each designated in their entireties by the letter E. Each of said plungers comprises the cylindrical central portion 150, that extends into a guide opening of one of the shelves 70. A threaded shank 151 with a nut 152 extends from each portion 150. At the upper end of the portion 150 is formed a rectangular head 153 that has formed therewith the journal bracket 154. A work supporting plate 155 is pivoted to each journal bracket 154, by means of the screw pivot 156. Each plate 155 has formed therewith the nose 158 and the heel 159. A spring 160 has its upper end fastened to the central portion 150 and its lower end bears on the shelf 70. It will 110 be noted that the plates 155 are on opposite sides of the ridge forming head 82. 115

A rock shaft 163 is supported in the journal bearings 33 and 35 and has attached to its front end the rock arm 164. A curved 120 needle 165 is clamped to the rock arm 164. A supporting plate 168 is fastened to the lug 34 of the journal bearing 33. 125

A presser foot 170 has formed therewith the longitudinal guide opening 171 for the 130

feed dog 126 and the ridge forming head 82. A U-shaped bracket 172 extends from the said presser foot 170 and is fastened to the supporting plate 168 by means of the 5 screws 173. The rear end of the said presser foot is fastened to the bottom face of the body portion 28 of the main frame of the machine by means of the screw 174.

Connecting means are provided between 10 the main driving shaft 40 and the rock shaft 163 in the usual way, and in this instance comprises the following: A spherical shaped eccentric head 180 is fastened to the shaft 40. An arm 181 is fastened to the rock shaft 15 163. A pin 182 with a spherical head 183 is clamped by the arm 181. A link with the heads 184 and 185 connects spherical shaped eccentric head 180 and the spherical head 183.

20 A crank 188 with the crank pin 189 is fastened to the shaft 40. An oscillating sleeve 190 with the projecting lug 191 is supported on the crank pin 189. A screw pivot 192 extends from the body portion 28. An 25 oscillating link with the upper sleeve 193 and the lower eccentric strap end 194 is supported on the pivot 192. A connecting rod 195 at one end has fastened thereto the forked shaped member 196 which is pivoted 30 to the lug 191 of the sleeve 190, and a spherical shaped head 197 at its other end is seated in the eccentric strap end 194. A looper 198 is fastened to the forward end of the connecting rod 195 in the usual way.

35 To operate the blind stitching machine the table 45 is swung down by means of the chain 65, and the folded fabric 200 to be blind stitched is located between the presser foot 170 and the supporting plates 155, 40 after which the chain 65 is released. The tension of the springs 160 tend to lift the plates 155 with the fabric 200 thereon in proper position, so that the teeth of the feed dog 126 can engage said fabric. At the 45 proper times the ridge forming head 82 bears up against the said fabric, raises it, forms a ridge thereon and locates said ridge in the guide opening 171 of the presser foot 170, in the path of the needle 165. The 50 teeth 85 of the head 82 engage the said fabric as it swings.

The driving pulley 41 is turned by a belt not shown and thereby the main driving shaft 40 is turned, by virtue of which the 55 various moving elements of the machine are moved to perform their functions and the fabric 200 is fed under the presser foot 170.

Various modifications may be made in the 60 invention and the present exemplification is to be taken as illustrative and not limitative thereof.

Having described my invention what I 65 desire to secure by Letters Patent and claim is:—

1. In a blind stitching machine the com-

bination of a frame, a main rotating driving shaft journaled in the frame, a slidable arm having an elongated guide opening in the machine, a feed dog extending from said arm, a lever pivoted to said frame with one end connected to said arm, an eccentric on the driving shaft, a lever pivoted to the frame having bifurcated members contacting with said eccentric and having an adjusting arm extending therefrom, a link 70 with one end pivoted to said first lever and the other end adjustably connected to said adjusting arm, a second arm in the machine and a pivot supporting the second arm secured to the frame of the machine and extending through the elongated opening in the first arm, said second arm having a bifurcated end with the members thereof contacting with said eccentric.

2. In a blind stitching machine the combination of a frame, a main rotating driving shaft journaled in the frame, a slidable arm having a pair of elongated guide openings bearing against said frame, a feed dog 80 extending from said arm, a pivot extending from the frame extending through one of the guide openings in said arm, a second arm with a bifurcated end bearing against said first arm and supported on said pivot, a roller journaled to the second arm engaging the second elongated opening of the first arm, an eccentric on said shaft engaging the bifurcated end of the second arm, a bifurcated lever pivoted to the frame 90 of the machine with its bifurcated end engaging said eccentric and adjustable means for the said lever to reciprocate said first arm with its feed dog.

3. In a blind stitching machine the combination of a frame, a main rotating driving shaft journaled in the frame, an eccentric on said shaft, a slidable arm for the machine, a feed dog extending from said arm, a bifurcated lever pivoted to said frame 100 with its bifurcated end engaging said eccentric, and adjustable means between said lever and said arm to reciprocate said arm and feed dog with strokes of different lengths.

4. In a blind stitching machine the combination of a frame, a main rotating driving shaft journaled in the frame, an eccentric on said shaft, a slidable arm in the machine, a feed dog extending from said arm, a bifurcated lever with one end pivoted to said frame with its bifurcated end engaging said eccentric and having an adjusting arm, a second lever with a pair of arms pivoted to the machine, one of the latter arms connected to said slidable arm and a link connecting the other of said pair of arms and said adjusting arm.

5. In a blind stitching machine the combination of a frame, a main rotating driving shaft journaled in the frame, an eccentric 130

on said shaft, a slidable arm in the machine, a feed dog extending from the slidable arm, a bifurcated lever with one end pivoted to said frame with its bifurcated end engaging said eccentric and having an adjusting arm with a guide opening, a second lever with a pair of arms pivoted to the frame of the machine, one of the latter arms connected to said slidable arm, a pin extending through said guide opening, means to clamp said pin in different positions in said guide opening and a link connecting the other one of said pair of arms and said pin.

6. In a blind stitching machine the combination of an adjustable table, an oscillating shaft depending from said table, a crank arm with a crank pin extending from said shaft and a ridge forming head having a bifurcated leg pivoted to said table, said crank pin engaging said bifurcated leg to oscillate said ridge forming head with the oscillations of said shaft.

7. In a blind stitching machine the combination of an adjustable table, an oscillating shaft depending from said table, a crank arm with a crank pin extending from said shaft, a ridge forming head pivoted in said table and oscillated by said crank arm and pin, a pair of slidable spring actuated plungers guided in said table and a table pivoted to each of said plungers on opposite sides of said ridge forming head.

8. In a blind stitching machine the combination of a frame, an adjustable table hinged to the frame, tension and adjusting means for said table to maintain it in operative position, an oscillating shaft depend-

ing from said table, a crank arm with a crank pin extending from said oscillating shaft and a head with a ridge and teeth and having a guide opening pivoted in said table, said crank pin engaging said guide opening.

9. In a blind stitching machine the combination of a frame, an adjustable table hinged to the frame, tension and adjusting means for said table to maintain it in operative position, a driving shaft journaled in said frame, a shaft depending from said table, a crank arm with a crank pin extending from the latter shaft, means between the two shafts to oscillate the latter, and a ridge forming head having a guide opening pivoted in said table, said crank pin engaging said guide opening.

10. In a blind stitching machine the combination of a frame, a driving shaft journaled in the frame, an eccentric for the driving shaft, an adjustable table hinged to the frame, a shaft depending from said table, a ridge forming head pivoted in said table, connections between the latter shaft and the ridge forming head, a crank arm extending from the latter shaft, a lever with a bifurcated end pivoted to the frame of the machine, said bifurcated end engaged by the eccentric on the driving shaft and a link connecting said crank arm and said lever having the bifurcated end.

Signed at the borough of Manhattan, city of New York, in the county of New York and State of New York this 10th day of April A. D. 1923.

HYMAN I. RAPPAPORT.
